SELF-INKING MARKING DEVICE

Ivan Georg André Ljunggren, Solna, Sweden, assignor to Aktiebolaget Cryptoteknik, Stockholm, Sweden

Application May 8, 1947, Serial No. 138,919
In Sweden April 9, 1947

Term of patent 14 years

(Cl. D64—10)

To all whom it may concern:

Be it known that I, Ivan Georg André Ljunggren, of Ryttarvägen 1, Råsunda, in the city of Solna, Sweden, and subject of the King of Sweden, have invented a new, original, and ornamental Design for Self-Inking Marking Devices, of which the following is a specification, reference being had to the accompanying drawing, forming part thereof.

Figure 1 is a front perspective view of a self-inking marking device showing my new design, the end not shown being substantially the same as that shown and the rear being substantially plain; and

Figure 2 is a top plan view of the same.

I claim:

The ornamental design for a self-inking marking device, as shown and described.

IVAN GEORG ANDRÉ LJUNGGREN.
